(57) **CLAIM**

The ornamental design for an insulated drinking cup as shown and described.

DESCRIPTION

FIG. 1 is a perspective view from the front-top-right side of the insulated drinking cup showing the new design, and dotted circular area indicates that an enlarged view of the area is provided in FIG. 9;

FIG. 2 is a perspective view from the back-bottom-left side of the insulated drinking cup showing the new design;

FIG. 3 is a front view of the design shown in FIG. 1;

FIG. 4 is a back view of the design shown in FIG. 1;

FIG. 5 is a left view of the design shown in FIG. 1;

FIG. 6 is a right view of the design shown in FIG. 1;

FIG. 7 is a top view of the design shown in FIG. 1;

FIG. 8 is a bottom view of the design shown in FIG. 1; and,

FIG. 9 is an enlarged view of the area shown in dotted circle in FIG. 1.

The broken lines depict portions of the insulated drinking cup that form no part of the claimed design.

1 Claim, 9 Drawing Sheets
